COATING APPARATUS

George Boulton, deceased, late of Rochester, N. Y.,
by Jeannette B. Boulton, executrix, Rochester, N. Y., assignor to United Shoe Machinery Corporation, Paterson, N. J., a corporation of New Jersey

Application October 23, 1936, Serial No. 107,253

18 Claims. (Cl. 91—50)

This invention relates to apparatus for coating various articles, it being especially designed to apply latex or other cements to portions of shoe-uppers.

Upper cementers are employed to coat the margins of the uppers of shoes or of pieces which are to be assembled to form such uppers, over predetermined widths, which widths will vary for different types of work. An object of the invention is to provide for the convenient and effective application of such variable coating and with a sufficient body or thickness of the coating substance.

A feature of the invention by which this object is attained may be found in a coating-applying member and a coating-delivering member, each of which may be in the form of a rotatable roll, such members being of different widths and arranged to be positioned in different transverse relations to vary the width of the applying surface to which the coating substance is delivered. This may be by differently locating the delivery-roll transversely of the periphery of the applying roll. Herein is disclosed a bearing sleeve for a delivery-roll, which may be one employed to transfer cement or other coating substance from a supply-roll to an applying roll, which sleeve is supported for adjustment in a direction parallel to the axis of the applying roll. In this way, the extent to which the delivery-roll overlaps the applying roll may be altered so that only the particular portion of the width of the applying roll which corresponds to the area to be coated will receive the coating substance.

As another feature of the invention, opposite work-engaging members, relatively movable toward and from each other, are combined with a means for supplying a coating substance and a member for transferring the coating substance from the supply means for application to the work and movable into and out of active position, together with means arranged to control simultaneously the relation of the work-engaging members and the position of the transferring member. In the disclosed embodiment of the invention, we have an applying roll and an opposed pressure-roll movable toward and from the applying roll and a rotatable delivery-roll for the coating substance movable into and out of active position. A treadle-operated member has connections to it which produce movement of both the pressure-roll and the delivery-roll. Thus, by a single act, i. e., depression of the treadle, the operator may control the coating of the work and the delivery of the coating sub-

stance therefor. Aside from its utility as a work-feed-controlling member, the treadle is also useful as a cement-delivery-controlling member.

A further feature of the invention involves means for changing the relative location of the applying and pressure-rolls. These rolls are situated one above the other, and with them is associated means for varying their relation with respect to a vertical plane containing the axis of one roll. This may be accomplished by mounting upon a carrier the pressure-roll, this having below it the applying roll over which work advances to receive its coating, and moving the carrier to position the pressure-roll at different points along the path of advance of the work. By this arrangement, there may be controlled the extent of contact of the work with the applying surface in the direction of its advance and the manner in which the coating substance is presented to the work.

Other features of the invention will be evident upon consideration of the following description and claims.

In the accompanying drawings, Fig. 1 illustrates a particular form of the invention in broken side elevation;

Fig. 2 is a broken end elevation looking from the left in Fig. 1, and

Fig. 3 is a perspective view of the elements more closely co-operating with the work.

A frame 10 is arranged for mounting upon a bench or column. From the front of this frame projects an arm 12, through which extends a horizontal shaft 14 journaled in the frame and arm and having secured on its outer extremity an applying roll 16. This roll is shown as grooved circumferentially to furnish spaced annular projections 18 which are preferably grooved transversely upon their peripheries. The arrangement is such that upon the peripheral applying surface of the roll an adequate body of cement or other coating substance may be carried for application to the work. The shaft 14, and therefore the roll 16, is rotated from a horizontal shaft 20 turning in the upper portion of the frame 10 and in an arm 22 projecting therefrom above the frame-arm 12. Power may be impressed upon the shaft 20 through a pulley 24 fast upon its rear extremity. Secured to the shaft within the frame is a worm 26 meshing with a worm-wheel 28 carried by a downwardly and inwardly inclined shaft 30 journaled upon the frame. At the lower end of the shaft 30, it is joined for rotation to the shaft 14 by bevel-gearing 32. To guard against injury caused

by clogging, the worm-wheel 28 may be held frictionally upon its shaft between a lower disk 34 fast upon said shaft and an upper disk 36, splined to move along the shaft and forced downwardly by a spring 38 adjustable by a nut 40 threaded upon the shaft to determine the force to be transmitted by the worm-wheel. If undue resistance is offered to the rotation of the applying roll, the friction drive will slip and injury be prevented to the apparatus or to objects caught by the roll.

Attached to the frame-arm 12 and extending below the applying roll 16 is a receptacle 42 for the adhesive. The contents of the receptacle 15 may be renewed from time to time from a tank 44 resting upon a bracket 46. The delivery is through a pipe 48 and is controlled by a valve 50 therein. Journaled horizontally on the receptacle 42 is a shaft 52 carrying a supply-roll 54 fast upon it. This roll is rotated through belt-gearing 56 from the shaft 14, it running in the contents of the receptacle and raising this to be delivered by a transfer-roll 58 to the applying roll 16. The transfer-roll is supported upon a carrier-rod 60, which extends substantially parallel to the axes of the applying and supply-rolls from an arm 62. The arm turns loosely about a pin 64 which projects eccentrically from the outer extremity of and below the axis of a shaft 66 rotatable upon the receptacle 42. The roll 58 thus always rests upon the periphery of the supply-roll, receiving cement therefrom but being normally out of contact with the applying roll. This is as appears in Fig. 2 of the drawings.

Upon the inner end of the shaft 66 is secured an arm 68, joined by a link 70 to a lever 72 fulcrumed upon the upper portion of the frame. The outer end of the lever may be depressed by a rod 74 arranged for actuation by the operator, as by connection to an unillustrated treadle, against the force of a spring 76, by which the lever and link are normally raised against a stop 77 projecting from the frame-arm 22 over the lever. Movement of the lever is communicated yieldably to the link through a helical spring 78 surrounding said link between a collar 79 thereon and a projection 81 from the lever. The extent of movement of the transfer-roll under the influence of the connections to the rod 74 may be limited by a stop-screw 80 threaded through the arm 68 and contacting with a projection 82 from the receptacle 42. A spring around the screw 80 tends to hold it frictionally against accidental changes in position. Upon a lowering of the treadle rod 74, the transfer-roll travels up the periphery of the supply-roll 54 until it is in cement-delivering relation to the applying roll 16. The extent of approach and therefore the quantity of cement delivered may be altered by adjustment of the stop-screw 80.

It may be desired to apply to the work stripes of the coating substance of different widths. For this purpose, the transfer-roll 58 is adjustably mounted transversely of the applying roll, so more or less of its length will be positioned opposite said applying roll to deliver thereto. The transfer-roll is free to rotate upon a sleeve 84, being held against longitudinal movement thereon by shoulders on the sleeve. The sleeve is threaded upon the carrier-rod 60 and has at its outer end a finger-piece 86 for convenience in rotating it. By this mounting, the transferring roll may be adjusted across the face of the applying roll so that different longitudinal portions deliver thereto, while the remainder turns idly

outside both the supply-roll and the applying roll, neither receiving nor delivering cement. The thickness of the layer of adhesive brought up from the receptacle upon the periphery of the supply-roll may be governed, before it reaches the transfer-roll, by a scraper 88 movable in guides 90 upon an upper receptacle-wall and adjustable toward and from the supply-roll by a screw 92.

The work is advanced for coating upon its under side by the roll 16 over a table 94 secured at its rear and forward extremities to the receptacle 42. In the table is an opening through which the upper portion of the applying roll rotates for engagement with the work. Just in front of this opening the table is depressed at 96 so that for a time, after the action of the roll upon the work, the freshly applied coating will be free from contact with the table. Any drip from the work may find its way into the receptacle through 20 openings at the opposite sides of the depressed portion of the table. To variably determine the width of the margin of the work presented to the applying roll, an edge-gage 98 is provided, this being secured adjustably to the top of the table 25 94 just to the rear of the applying roll by a slot-and-screw connection 100. The gage is shown as hooked to overhang the material and prevent its upward displacement. As appears in Fig. 1, width or size designations may be inscribed at 30 102 upon a vertical wall at one end of the table adjacent to the edge-gage, as a guide for the operator in setting said gage.

To hold or grip the work in such engagement with the applying roll 16 that it will be effectively 35 coated and advanced thereby, a pressure-roll 104 is arranged above said applying roll. This pressure-roll is shown as freely rotatable about a spindle 106 extending horizontally between the arms of the forked extremity of a rod 108 sliding 40 in spaced bearing-ports 110, 110 projecting from a carrier-plate 112. The plate is mounted upon the outer extremity of the frame-arm 22 and is pivoted for angular adjustment about the end of the shaft 20, where it extends beyond 45 the frame-arm. It is fixed to the arm in the chosen position by slot-and-screw connections 114, 114. The roll 104 is held against turning about the axis of the rod 108 by a finger 116 projecting from said rod and entering a vertical 50 slot in the plate 112. It is normally spaced from the applying roll to an extent determined by a stop-collar 118 contacting with the upper bearing-portion 110 of the plate, by a spring 120 surrounding it between the finger 116 and the lower 55 bearing-portion. It is lowered to apply pressure to the work by engagement of a lateral extension 121 from the forward extremity of the lever 72 with the upper edge of the finger. The approach of the pressure-roll to the applying roll is limited 60 by a nut 122 threaded upon the top of the rod 108 and arranged for contact with the upper plate-portion. The thickness of the applied coating may be varied by a change in the location of the pressure-roll 104 with respect to a vertical 65 plane through the axis of the applying roll, so it will assume different positions along the path through which the work travels. For example, if the pressure-roll is so adjusted by means of the slot-and-screw connections 114 that it is 70 carried to the right of the center line of the applying roll (Fig. 2), it will cause the work-piece to engage the applying roll through an increased peripheral angle. At the same time, there will be a greater tendency for a body of the adhesive 75

to gather in the wider pocket which is formed between the upgoing side of the roll and the work. In preparing the apparatus for operation, the coating substance is fed from the tank 44 until it reaches the desired depth in the receptacle 42. Thereafter, the feed may be continuous and gradual or in larger quantities intermittently, this being determined by the adjustment of the valve 50. According to the width of the marginal coating to be applied, the transfer-roll 58 may be adjusted transversely of the applying roll by the finger-piece 86, thereby causing the chosen extent of the applying roll to receive the adhesive from the supply-roll 54. The edge-gage 98 is correspondingly positioned. Power being applied to the pulley 24, the rolls 16 and 54 are rotated continuously in directions indicated by the arrows in Fig. 2. The operator inserts the end of a work-piece W (Fig. 3) over the table 34 between the applying roll and the pressure-roll 104, the latter being at the time raised by its spring 120, and draws down the rod 74. The lever 12 thereupon lowers the link 70, producing a clockwise movement of the eccentric pin 64, as viewed from the front of the apparatus. This causes the transferring roll to ascend the periphery of the supply-roll until it is stopped by the screw 80. It is now in position to deliver cement from the supply-roll to the applying roll. Upon continued downward movement of the rod 74, the spring 78 yielding because of the stop-contact 80, 82 for the transfer-roll, the lever-extension 121 by its engagement with the finger 116 carries down the pressure-roll through a distance fixed by the stop-nut 122. This forces the work against the applying roll, so both its advance and coating are effected as the result of the rotation of said applying roll. The thickness of the applied coating may be varied by adjustment of the delivering position of the transfer-roll transversely of and toward and from the applying roll, through the positioning of the scraper 88 for the supply-roll and by the location of the pressure-roll 104 relative to the applying roll. When the desired length of the work-piece has been coated, the operator releases the rod 74, and the elements return to their initial positions.

Having described the invention, what is claimed as new and which it is desired to secure by Letters Patent of the United States is:

1. In a coating apparatus, coating work-gripping rolls of similar width, one of said rolls having a coating-applying periphery, a rotatable roll narrower than the applying roll and delivering a coating substance to the periphery of the applying roll, and means arranged to vary the position of the delivery-roll transversely of the periphery of the applying roll without varying the relation of the latter to the coating work-gripping roll.
2. In a coating apparatus, a rotatable roll having a coating-applying periphery, a rotatable roll of different width delivering a coating substance to the periphery of the applying roll, a bearing upon which the delivery-roll is rotatable but as to which said delivery-roll is held against axial movement, and means for supporting the bearing in different positions transversely of the periphery of the applying roll.
3. The combination with a rotatable cement-applying roll, of a support extending substantially parallel to the axis of rotation of the applying roll, a sleeve mounted upon the support for adjustment longitudinally thereof, and a cement-delivering roll which is rotatable upon the sleeve,

is adjustable axially therewith, and cooperates with varying portions of the applying roll.

4. The combination with a rotatable cement-applying roll, of a support extending substantially parallel to the axis of rotation of the applying roll, a sleeve threaded upon the support, and a cement-delivering roll rotatable upon the sleeve and held against movement longitudinally thereof and co-operating with the applying roll in different relations thereto.

5. In a coating apparatus, a cement receptacle, a supply roll dipping in the cement in the receptacle, an applying roll separated from the supply roll, a transfer roll having a diameter greater than the distance between the before-mentioned rolls, a loosely supported arm on which the transfer roll is mounted, whereby the transfer roll rests against one of the other rolls, and an operator-controlled device for moving said arm to cause the transfer roll to ride along the surface of one of the rolls on which it rests until it contacts with the other roll whereby it becomes effective to deliver coating material to the applying roll.

6. The combination with a rotatable cement-applying roll, of a cement-receptacle, a supply-roll rotatable in the receptacle, a transfer-roll situated between the applying roll and the supply-roll, an arm upon which the transfer-roll is rotatable, an eccentric mounting for the arm, said mounting being rotatable to carry the transfer-roll into and out of cement-transferring relation to the supply-roll and applying roll, a work-feeding mechanism, a treadle controlling said mechanism, and a connection from said treadle to the aforesaid eccentric mounting arranged to control the transfer of cement.

7. The combination with a rotatable cement-applying roll, of a cement-receptacle, a supply-roll rotatable in the receptacle, a transfer-roll situated between the applying roll and the supply-roll, and an arm carrying said transfer-roll and loosely supported to permit said transfer-roll to rest against the supply-roll and movable by the operator to bring said transfer-roll into and out of active operative relation to said applying roll, the transfer-roll being also movably mounted on said arm for adjustment transversely of the applying roll.

8. The combination with a rotatable cement-applying roll, of a cement-receptacle, a supply-roll rotatable in the receptacle, an arm movable by the operator and having a rod projecting from it substantially parallel to the axis of the applying roll, a transfer-roll carried by the rod and movable into and out of contact with the applying roll, and means arranged to position the transfer-roll at different points longitudinally of the rod.

9. In a coating apparatus, opposite members engaging opposite faces of the work and arranged to effect its coating on one face, said members being arranged for relative movement toward and from each other to grip or to release the work, means for supplying a coating substance, a member for transferring the coating substance from the supply means to one of the work-engaging members for application to the work, said transferring member being movable bodily into and out of active position, and means arranged to control simultaneously the relation of the work-engaging members and the position of the transfer member.

10. In a coating apparatus, opposite work-engaging rolls movable to advance and coat the work, said rolls being arranged for relative move-

- ment toward and from each other to grip or to release the work, means for supplying a coating substance, a rotatable roll for transferring the coating substance from the supply means to one of the work-engaging rolls for application to the work, said transferring roll being movable bodily into and out of active position, and a member movable by the operator to control both the relation to the work of the work-engaging rolls and the position of the transfer-roll.
11. In combination, a rotatable cement-applying roll, a rotatable pressure-roll movable toward and from work-gripping relation to the applying roll, a roll movable bodily to deliver cement to the applying roll, a member movable by the operator, and connections from the member to move both the pressure-roll and delivery-roll.
12. In combination, a cement-receptacle, a supply-roll rotatable therein, a cement-applying roll, a bodily movable transfer-roll arranged in one position for active co-operation with both the supply-roll and the applying roll, said transfer-roll being movable into and out of such active position, a pressure-roll movable into and out of work-gripping relation to the applying roll, and a member for actuation by the operator to move both the transfer-roll and the pressure-roll.
13. The combination with a rotatable cement-applying roll, of a cement-receptacle, a supply-roll rotatable in the receptacle, a transfer-roll situated between the applying roll and the supply-roll, a movable arm upon which the transfer-roll is rotatable, a pressure-roll movable into and out of work-gripping relation to the applying roll, a lever by which the movement of the pressure-roll is effected, and connections between the pressure roll lever and the transfer-roll arm arranged to impart the movement of one to the other.
14. In a coating apparatus, a rotatable applying roll for a coating substance, a rotatable pressure-roll, the rolls being situated with their axes positioned one above the other, and movable supporting means for one roll arranged to vary the relative positions of the rolls in a direction along the path of movement of the work, the path of movement of said supporting means carrying the axis of its roll to either side of a vertical plane containing the axis of the other roll.
15. In a coating apparatus, a frame, a receptacle for a coating substance mounted thereon, an applying roll rotatable on the frame above the receptacle and supplied with the coating substance therefrom, the work advancing over the applying roll to receive the coating, a carrier movable on a frame, and a pressure-roll mounted upon the carrier and movable thereby to different points along the path of advance of the work.
16. In a cementing apparatus, an applying roll to which cement is supplied, a carrier pivoted to swing about an axis parallel to that of the applying roll, means arranged to secure the carrier in different angular positions, and a pressure-roll rotatable upon the carrier below said axis and co-operating with the applying roll, the movement of the carrier being effective to move the applying roll substantially horizontally.
17. In a cementing apparatus, a frame provided with an arm, a cement-receptacle mounted upon the frame, an applying roll rotatable upon the frame above the receptacle and supplied with cement therefrom, a plate movable upon the end of the frame-arm in a plane normal to the axis of the applying roll, means arranged to secure the plate in different positions, and a pressure-roll slidably mounted upon the plate to engage the work in cooperation with the applying roll and in various relations thereto.
18. In a cementing apparatus, a frame provided with an arm, a cement-receptacle mounted upon the frame, an applying roll rotatable upon the frame above the receptacle and supplied with cement therefrom, a plate provided with bearing-portions and pivoted upon the end of the frame-arm, arcuate slot-and-screw connections between the plate and arm, a rod slidable in the bearing-portions of the plate, and a pressure-roll rotatable upon an axis normal to that of the rod and co-operating with the applying roll at an adjustably selected point along the path of the work.
